UNITED STATES PATENT OFFICE

2,541,471

FURNACE FOR PYROLYZING KETENIZABLE
ORGANIC COMPOUNDS

David C. Hull and William R. Saunders, Kingsport, Tenn., assignors to Eastman Kodak Company, Rochester, N. Y., a corporation of New Jersey

Application July 11, 1947, Serial No. 760,482

4 Claims. (Cl. 23—277)

1

This invention relates to a process and apparatus for the pyrolysis of organic compounds and more particularly to a process and apparatus having increased capacity for the pyrolysis of ketenizable compounds such as acetone, acetic acid, and the like to produce ketene or other valuable products.

Certain processes for the pyrolysis of ketenizable materials and apparatus therefor are described in prior Patents 2,232,705 and 2,393,778 to D. C. Hull, a co-inventor of the present invention. The present invention is concerned with the same general type of process and apparatus as described in the Hull patents aforesaid but constitutes an improvement thereover in a number of respects as will be set forth herein.

In general the pyrolysis of ketenizable materials is accomplished by various steps such as vaporizing the materials, preheating, and/or superheating the vapors and pyrolyzing the superheated vapors. The temperatures involved for the various operations may range between 300° or 400° C. to 1200° C. or higher. Therefore, it is apparent that for certain of the steps special metal tubes and coils are required for satisfactory commercial operation. In the practice of the invention described herein we prefer to use the coils and a number of other parts manufactured in accordance with the description set forth in companion Patents 2,232,705 and 2,393,778 aforesaid.

The addition of catalyst to the ketenizable materials to be pyrolyzed, the application of reduced pressure to the pyrolysis reaction, the condensation or other treatment of the pyrolysis products, and the like, as carried out in the present invention, (excepting that the larger quantities are processed in the present invention) may be substantially in accordance with existing practices. Hence, extended description of such features herein is unnecessary.

As is readily apparent, the operation of such pyrolysis processes requires the input of considerable amounts of heat. This has been accomplished heretofore by operating conventional burners in combustion chambers and permitting combustion products in their flow through the apparatus to contact the various coils—the super heater coil, the pyrolysis coil and the like, as best possible, the organic materials in the coil picking up the heat required for cracking or pyrolysis.

That is, as may be noted from the drawings of Patent 2,232,705 and 2,393,778, there is a fixed

2

heating chamber equipped with burners. This heating chamber is in series with a pyrolysis chamber and a preheat or superheat chamber. As shown, these chambers are bricked in, and hence of a more or less fixed external size and construction. As may be further noted from the drawing of the patents aforesaid, the coils within these chambers do not completely fill the space.

10 In the prior apparatus and processes, while some increase in capacity might be obtained merely by feeding more materials under a higher pressure and rate of feed through the apparatus and supplying more fuel to the burner to furnish 15 a greater amount of heat, such increase in capacity obtainable was not of great magnitude, because if too large a quantity of ketenizable organic fluid such as acetic acid vapors, were forced through the coils, at some instant, part of the 20 acid would not be pyrolyzed. Unpyrolyzed product or partially pyrolyzed product would be obtained, thereby reducing the efficiency and yields obtainable in the process. In other words, existing 25 apparatus may be generally regarded as having a more or less fixed capacity which heretofore appeared to be increaseable only by general enlargement of all parts which would, of course, necessitate the enlargement of the external enclosures such as the furnace housing around the 30 various coils.

However, in accordance with the present invention we have found that by certain changes internally of the apparatus, which changes may be more or less readily added to existing equipment, substantially increased capacity may be 35 obtained without overall alteration of furnace size or otherwise materially changing the external furnace housing. In other words, we have found that increased capacity may be obtained 40 without generally changing the diameter of the various coils or other overall dimensions of the equipment. However, if desired the diameter of the coils may be increased somewhat, as well as changes made in certain other dimensions, such 45 as increasing the length of the coils, for example, to such an extent only that it is not required to materially change the housing or other external dimensions of the furnace. We have found that by making the improvements of the present invention, not only is the capacity of a furnace of 50 a given external size increased, in that it delivers more desired product, but also the quality of the product and the efficiency of the process are in no way impaired.

55 This invention has for one object to provide

a method, having increased capacity, for the pyrolysis of organic compounds such as ketenizable material exemplified by acetic acid, acetone, and the like. A further object is to provide an apparatus and process of increased capacity for the production of ketene by the pyrolysis of ketenizable compounds under relatively high temperature conditions. Still another object is to provide an apparatus and process of the class described wherein substantially increased capacity may be obtained in equipment having the same relative external size and otherwise occupying relatively the same amount of floor space. Still another object is to provide improvement features which may be applied to existing equipment for the pyrolysis of ketenizable materials to obtain increased capacity therefrom. Still another object is to provide improved means and procedure for supplying heat to, and heating in, processes of the class described. Still a further object is to provide process and apparatus for the pyrolysis of ketenizable materials wherein a substantial part of the pyrolysis is accomplished by radiant heating. Still a further object is to provide improved apparatus and processes of increased capacity for the pyrolysis of acetic acid to ketene. Other objects will appear hereinafter.

We have found that in apparatus and processes for the conversion of ketenizable materials by pyrolysis to ketene that greatly increased capacity can be obtained without loss of efficiency or reduced yields or by requiring greater floor space for the apparatus, by interposing certain bodies, preferably refractory members within the space encircled by the superheating and/or pyrolysis coils which internal space is now unfilled and unused, and by certain other arrangements made internally in the furnaces such as lengthening the various coils either with or without changing the coil diameter. However, both increased diameter and length of coil may be accomplished as well as certain other internal changes accomplished as will be described in detail hereinafter.

For a better understanding of our invention reference will be made to the attached drawing forming a part of the present application.

In the attached drawing—

Figure 1 is a semidiagrammatic side elevational view, largely in section and partly on exaggerated scale for clarity, showing an arrangement of apparatus parts in accordance with one embodiment of the present invention.

Figure 2 is a more detailed view, partly in section in which certain of the parts have been omitted and others shown in side elevation for better illustrating the positioning and structure of some of the addition members in accordance with the present invention.

In considering the drawing, and in particular Figure 1, it will be noted that a number of the parts are the same or similar to those described in companion Patents 2,232,705 and 2,393,778, but over which the present invention constitutes an improvement.

Referring to Figure 1, an inlet 2 is provided for the introduction of ketenizable material, as for example, vapors of acetic acid. This inlet is connected to a coil 3 which in this particular embodiment is termed a preheater coil. While the structure shown and described in the present application as a preheat chamber represents an improvement in the utilization of the effluent gases, in their passage to the stack, the present invention is directed more to the construction of the

environment with respect to the coils 6 and 8, which two coils may be compared with the two coils shown in the drawings of the aforesaid patents.

Reference is now made to the parts with which the present invention is particularly concerned. The exit from the preheater coil is connected in series by means of a U conduit 4, with a superheater coil 6. This superheater coil is connected in series by means of U conduit 7 with the pyrolysis coil 8. The last mentioned coil is provided with outlet tube 9, which may be suitably connected to a condensing device or the like such as shown in the patents aforesaid.

It will be observed that the various coils and connections may be generally the same as the corresponding parts shown in the Patents 2,232,705 and 2,393,778. That is, the connections may be either internally or externally of the furnace. The coils are constructed of chromium-nitrogen or chromium-aluminum steels as described in these patents. Inasmuch as such details are set forth in said patents, extended description herein is unnecessary.

It will be further noted that the overall outside dimensions of the instant housing 11 for the coils as well as the diameter of the coils, may be the same. In other words, it is not necessary, in accordance with the present invention, that the apparatus be any larger externally or require a materially greater amount of floor space than existing equipment although increased capacity is obtained by the construction of the present invention. It will be observed, however, that the several coils in the apparatus of the present invention, as compared with the construction described in the patents aforesaid, are longer in that they substantially fill the entire space from top to bottom within the housing 11. In addition to lengthening the coils it is also possible to increase the diameter thereof if this is desired.

That is, by virtue of the improvements of the present invention wherein, for example, heating may be accomplished over all or at least a major portion of the external surface of the coils (both outer and inner external surfaces), it is now possible to heat larger diameter coils up to suitable temperatures. However, the latter feature of increasing coil size is optional.

In other words referring further to Figure 1, within furnace housing 11 there are a plurality of partition walls designated 12, 13, and 14. These partition walls separate the furnace into a plurality of chambers designated preheater chamber 21, superheater chamber 28, and pyrolysis chamber 29. The coils in these respective chambers extend substantially the full height of the chamber as designated by the extension on the coils 17 and 18. By this construction the coils extend substantially from the top of the furnace housing to the bottom thereof as already mentioned.

Referring further to Figure 1, positioned within the space encircled by said coils, a space which has heretofore been unutilized, in accordance with the present invention there are positioned cylindrical or other shaped heat absorbing members designated 22 and 23. These members may be made up of several sections and of certain materials. Further information concerning the construction of these important parts will be set forth in connection with the description under Figure 2.

In passing it is desired to point out that with respect to chamber 21 certain improvements may

be made in the construction and the recovery of heat from the effluent combustion gases as these combustion gases pass to the stack. As shown, coil 3 may be lengthened as at 16 for more completely filling chamber 27. Also, within the space encircled by this coil 3 there may be placed a refractory member, such as 21. This member may be hollow so that the effluent combustion gases may pass therethrough to the stack. In so passing member 21 is heated and is thereby able to give off heat to the interior periphery of coil 3. However, as indicated above, the addition of this improved construction in the space between the last chamber of the series and the stack depends to some extent upon existing constructions. In many existing constructions the improved heat recovery arrangement just described may be incorporated as a supplement to or as a replacement for existing heat recovery devices now used for recovering the last amounts of heat from effluent gases prior to their discharge from the stack. A vent, opening, or other passageway means is provided at 24 for permitting the combustion products to escape to the stack.

Partition wall 12 is so arranged as to provide an opening 26 so that combustion products gain access to chamber 27 and flow therethrough. The opening 26 connects with the superheater chamber 28 down through which, in that embodiment of the invention being described, the combustion products may flow.

The upper portion of chamber 28 is provided with a brickwork passageway 34 and a plurality of concentric passageways 32 and 33 for connecting the superheater chamber with the pyrolysis chamber 29 in which there is upflow of heating medium. That is, provided in the upper portion of chamber 29 a plurality of radially positioned openings 30 and 31 lead to the concentric passageways 32 and 33, which in turn are connected by the brick passageways which are in series with chamber 28.

Pyrolysis chamber 29 is connected to a suitable burner chamber, as shown, by means of the opening 35. Since the burner feature may be as shown in the above-mentioned Hull patents, the disclosure of further details herein is unnecessary. Likewise, the furnace housing 11 may be constructed from metal parts, brick parts or special composite heat-resisting materials such as metal-asbestos and the like.

While in the particular embodiment described the encircled members 22 and 23, have been shown as supported from the base of the furnace housing, these members may be suspended from the upper portion of the housing and the various partition walls correspondingly adjusted for obtaining the up and down flow of combustion products through the furnace.

As will be described in detail, it is preferred that a part, such as the surface of, or if desired, the entire partition walls, such as partition walls 12, 13, and 14, as well as the members 22 and 23 in the space encircled by the coils, be constructed in a special manner and of special materials as will be described in detail under Figure 2.

Referring to Figure 2 which shows the several members 22 and 23 with the encircling coils removed, these members in the embodiment shown are made up of a plurality of sections 41, 42, and 43, for example, held together by rods such as 44, which rods are embedded in the base of the furnace housing or otherwise securely positioned. In general, the overall shape of members 22 and 23 preferably will be that which most closely

conforms to the space encircled by the coils but spaced from the coils somewhat to permit easy installation as well as to permit of some expansion or thermal distortion which may occur at the high temperatures prevailing within the apparatus. In general, the members may be cylindrical with suitable notehout openings therein as may be required to permit the coil to cross over and return to the top of the furnace housing. However, other shapes than cylindrical and constructions such as hexagonal may be employed as long as the space encircled by the coil is at least partly filled. These members, as well as partition walls 12 and 13 and likewise the walls facing the exterior of said coils are preferably constructed of materials having the property of radiant heating and heat absorbing. The various refractory carbides, such as silicon carbide, are preferred, although fire brick or equivalent materials that will withstand the temperatures to which the interior of the units are to be subjected may also be employed. Or, for example, as shown, certain members, as member 21 may be constructed of metal, preferably a metal which will give off heat radiantly and withstand the heating, such as alloy cast irons and steels. For example, the various chromium and nickel-chromium irons and steels or aluminum may be used.

The various concentric passageways, such as 33, may be of conventional construction and merely function to conduct the combustion products, at a slowed down rate and without channeling, so that there is an even flow which, when ejected into the respective chambers, flows in a manner conforming to the coils and with relatively even distribution. The checker brick at 34 may be of conventional pattern and is provided for retarding the flow of the gases from chamber 29 which is the chamber, in the embodiment shown, at the highest temperature. The passageways, such as at 26, may be relatively unobstructed.

In the operation of our process the materials to be pyrolyzed, such as acetic acid vapors, are introduced at 2. Any usual catalyst, such as a phosphate, may be present in the vapors. In passing through the various coils 3, 6, and 8 the materials are suitably heated and pyrolyzed so that the product of the pyrolysis leaving at 9 may be condensed to recover the ketene. While the passage of the ketenizable materials through the apparatus and the reaction products obtained are similar to those described in the above-mentioned Hull companion patents, we have found that the capacity (quantity of throughput) is greatly increased. This increase is readily apparent from the data set forth in the table below.

In this table a comparison is made with the throughput and yield through a furnace in which the space encircled by the coils contained no members comparable to members 22 and 23 or other construction in accordance with the present invention. However, in the runs below all other conditions were maintained as nearly the same as possible. That is, the same catalyst and other additions, in the same ratios, were used in each instance. It is, of course, apparent that with the same ratio of catalyst, for example, a greater amount thereof is fed in accordance with the present invention because a greater amount of acetic acid is fed due to the increased capacity obtainable by the present invention. The units of feed were by weight. The yield represents the percentage of the feed converted to the desired

product in a single pass through the apparatus. The acid number is another measure, of an empirical nature, of the efficiency. This measure is applied to certain effluents. If the number runs high that indicates more acid feed is going through the apparatus without conversion than in an instance where this number is low.

No.	Construction in Accordance With Prior Art			Construction in Accordance With the Present Invention		
	Feed	Yields	Acid Number	Feed	Yields	Acid Number
1	1,200	80	42	1,800	82	38
2	1,000	84	36	1,600	84	36
3	1,050	82	38	1,550	82	38
4	950	85	34	1,650	85	34

From the above table it will be observed that in general the capacity (increase of feed) was increased at least 50% without sacrifice of yield. In other words, for the same external size furnace occupying the same amount of floor space in the plant, it was possible to supply a substantially greater amount of feed to this unit and convert it to the desired product. Consequently, it may be seen that by the application of the present invention to existing equipment or in the construction of new equipment two of the present units would be approximately equivalent to, or better than, three units of prior construction. For the same floor space it is therefore possible to obtain greatly increased production or a predetermined production may be obtained by smaller floor space. The advantages are further reflected in that, even though there is substantially increased capacity, the expense of constructing the furnace housing is not materially changed. Also no increase in costs is required for installing additional controls or ancillary equipment for the construction of the present invention which gives increased capacity.

In other words, the same number of burners for combustion purposes will suffice, although in preferred operation, rather than employing a single burner delivering a certain amount of heat, it is preferred to employ a plurality of smaller burners and burners of a type which deliver a radiant heating type of combustion product and heating medium, as it appears that this may contribute to even further increased capacity.

While it is not desired to be bound by any theory of operation respecting the present invention or the advantages obtained by the present construction, the following theory concerning the operation of the present apparatus and process may constitute an explanation for the improved results obtainable and is set forth primarily as an aid to a better understanding of the present invention.

As described at the outset, the present processes of converting and pyrolyzing ketenizable materials may require operation of the pyrolysis zone at temperatures in excess of 700 or 800° C. and, for example, even at 900° or 1000° C., depending upon various factors such as the degree of reduced pressure on the system, the speed with which the ketenizable materials are being passed through the apparatus and the like. In addition, as referred to above, the reaction involved in converting a ketenizable material, such as acetic acid, to ketene is endothermic and consequently requires a high heat input.

It is known that heat may be transmitted in several ways such as, for example, by convection, by conduction, and by radiation. It is also

known that, in general, heat transfer increases as the temperature increases. However, with respect to heat transfer the heat transferred by radiation under certain conditions may be substantially greater than in heat transfer by conduction. In the particular processes under description we have found that the best heat transfer can be obtained primarily by radiation.

In prior constructions where the combustion products comprising the heating medium were permitted to pass in a baffled manner over and above the coils, pyrolysis was presumably accomplished by heat transferred largely by convection and conduction.

In the construction of the present invention wherein the particular members 21, 22, and 23 are positioned within the space encircled by the coils, as well as by other members capable of radiant heating, preferably on the surface or throughout the several partition walls, it is possible to increase the heat supplied by radiation, which is particularly effective by virtue of its striking a substantial portion of the entire surface of the various coils (both the inner periphery and outer periphery thereof). By the various checker brick and concentric passageway arrangements, the heating medium is delayed in the pyrolysis chamber sufficiently long so that all portions thereof, including member 23, acquire heating energy which is released as radiant heat to the pyrolysis. Similar remarks apply to heating in the several other chambers. In addition there is also obtained heat input to the reaction by convection and conduction from the passage of the heating medium from the burner chamber to the outlet flue.

Moreover certain products of combustion, namely the heating medium itself, are capable of giving off thermal energy in the form of radiant heat. Therefore, by controlling the combustion in the burner chamber further radiant heat may be obtained in this manner. In general, we may use oil, gas, or the like fuels. We prefer to operate the combustion so that the coils do not carbon-up extensively. If carbon forms on the coils, it may ignite and burn on the coils with attendant injury.

However, irrespective of the theory of operation, we have found the construction, as fully disclosed herein, permits a substantial increase in capacity in process and apparatus of the class described and production of ketene of quality and richness at least as high as that obtained in prior art operation. As indicated, the external size of the apparatus does not have to be materially increased, if at all, nor is greater floor space required for our apparatus.

It will be apparent that certain other changes may be made without departing from the spirit of the present invention.

We claim:

1. An apparatus for the pyrolysis of a ketenizable organic compound to produce ketene which comprises a furnace housing made up of top, bottom and side walls and containing three interconnected chambers which are separated from each other by partition walls extending partially across the interior of the housing, a vertically extending coil in each of said chambers, each of said coils extending substantially the entire vertical distance between the top and bottom of the housing, said coils being constructed of a chromium-containing steel, means for connecting said coils in series, vertically extending silicon carbide refractory core members pos-

tioned within a substantial part of the space encircled by said coils, said refractory members being made up of a plurality of sections held together by means securely attached to the furnace housing and means associated with said apparatus for supplying hot combustion gas to one of said chambers, and means of withdrawing said hot gas from another of said chambers after it has passed through all three chambers and in contact with said refractory core members.

2. An apparatus for the pyrolysis of a ketenizable organic compound to produce ketene which comprises a furnace housing, made up of top, bottom and side walls and containing three interconnected chambers which are separated from each other by partition walls extending partially across the interior of the housing, a vertically extending coil in each of said chambers, each of said coils extending substantially the entire vertical distance between the top and bottom of the housing, means for connecting said coils in series, vertically extending refractory core members positioned within a substantial part of the space encircled by said coils, said refractory members being made up of a plurality of sections held together by means securely attached to the furnace housing, and means associated with said apparatus for supplying hot combustion gas to one of said chambers, and means for withdrawing hot gas from another of said chambers after it has passed through all three chambers and in contact with said refractory core members.

3. In an apparatus for the pyrolysis of ketenizable organic compounds to produce ketene, comprising a furnace housing made up of top, bottom and side walls and containing three interconnected chambers which are separated from each other by partition walls extending partially across the interior of the housing, a vertically extending coil in each of said chambers, means for connecting said coils in series, means associated with said apparatus for supplying hot combustion gas to one of said chambers, and means for withdrawing combustion gas from another of the chambers, after the combustion gas has passed through all three chambers, the improvements characterizing the apparatus which comprises the features that said vertically extending coils extend substantially the entire vertical distance between the top and bottom of the housing and contain vertically extending refractory core

members positioned within a substantial part of the space encircled by said coils, said refractory core members being made up of a plurality of sections held together by means securely attached to the furnace housing.

- 5 4. An apparatus for the pyrolysis of a ketenizable organic compound to produce ketene which comprises a furnace housing made up of top, bottom and side walls and containing three interconnected chambers for preheating, superheating and pyrolysis, partition walls between the chambers which extend partially across the interior of the housing, a vertically extending coil in each of said chambers, said coils extending 10 substantially the entire distance between top and bottom of the housing, means for connecting the coils in series for preheating, superheating and pyrolysis as aforementioned, vertically extending refractory core members positioned within at least two of said coils, said core members occupying a substantial part of the space encircled by the coils which contain core members therein, said refractory core members being made up of a plurality of sections held together 15 20 25 30 35 by means securely attached to the furnace housing and means associated with said apparatus for supplying hot combustion gas to one of said chambers and means for withdrawing hot gas from another of said chambers after the combustion gas has passed through all chambers and in contact with the refractory core members aforementioned.
